UNITED STATES PATENT OFFICE.

JOHN C. McLAUGHLIN, OF JERSEY CITY, NEW JERSEY, ASSIGNOR TO UNDERWOOD
TYPEWRITER COMPANY, OF NEW YORK, N. Y., A CORPORATION OF DELAWARE.

TYPE-WRITING MACHINE.

1,021,158.

Specification of Letters Patent. Patented Mar. 26, 1912.

Application filed September 24, 1910. Serial No. 583,549.

To all whom it may concern:

Be it known that I, JOHN C. McLAUGHLIN, a citizen of the United States, residing in Jersey City, in the county of Hudson and State of New Jersey, have invented certain new and useful Improvements in Type-Writing Machines, of which the following is a specification.

This invention relates to card holders attachable to the cylindrical platens of type-writing machines. Devices of this class have usually been constructed of a strip of metal arched to conform to the circumference of the platen and extending along the platen, tongues being provided to catch over the card; the ends of said strip usually having forked arms to bestride the hub of the platen, with means to catch over the heads of the platen. By the use of such holders, the platen was liable to become worn or indented in one place, this being due to writing a large number of cards thereon.

The objects of the present invention are to improve and simplify card holders, and to render them more simple and readily attachable to the platen, and to lengthen the life of the platen. The card-holding strip is provided at opposite ends with means to catch upon any of a series of fasteners mounted at intervals about the peripheries of the respective heads of the platen. As there are a number of different points at which the card holder may be applied to the platen, the particular point of application each time will be determined entirely by chance and with a machine in ordinary use, a great number of applications of the strip will be distributed fairly uniformly at the different points. In this way the platen successively presents a number of different portions of its surface to the action of the type in writing on different sets of cards. For this reason the wear on the platen by the type is made uniform and distributed substantially over its periphery.

In the accompanying drawings, Figure 1 is a perspective of a platen having the present invention applied thereto. Fig. 2 is an end view. Fig. 3 is a part sectional detail view of the card holder disengaged from the platen. Fig. 4 is a similar view, the card holder and platen being engaged. Fig. 5 is a detail view showing the parts disassembled.

55. A strip 1 extends the length of the platen

2 and has a series of spring tongues 3 to catch a card 1^a. Springy sockets 4, mounted in the ends 5 of the strip, (which project over the usual platen heads 6 at opposite ends of the platen), are pressed down to snap over the heads of buttons 7 fixed to the opposite platen heads and close upon the necks 8 of such buttons, to secure the card holder on the platen. The socket or button holder 4 may comprise a shell closed at one end and having a shoulder 9 (Fig. 5) to rest on the upper edge of the opening 10 in the card holder. The shell is crimped to form a bead 11, which lies against the under edge of the strip around the opening 10 to hold the shell to the plate 1. Said crimping also bends the open slotted edge of the shell inwardly to form springy lips 12, which spread apart to admit the head of the button to the socket. The buttons 7 may be brazed to the platen heads, and may, if desired, project slightly above the circumference of the platen (Figs. 2 and 3), so as to be easily engaged by the sockets 4 which preferably extend but slightly below the under face of the strip 1. Each head is of such circumference that several such buttons 7 may be arranged about its periphery, the buttons on one head being opposite those on the other head to permit placing the card holder at different points around the platen, whereby no one portion of the platen surface becomes unduly worn or indented by the types. The holder is removed by placing one's fingers beneath the overhanging ends 5 of the strip and pressing outwardly.

Having thus described my invention, I claim:

1. In a typewriting machine, in combination, a rotatable platen having a row of fastening devices at one end thereof, a second row of fastening devices at the other end of said platen, the members of one row being opposite the members of the other row, a detachable card-holder strip having fasteners coöperating with said fastening devices to secure the same to said platen, said fastening devices being separated circumferentially on the face of said platen whereby successive applications of said strip will occur by chance at different points on the periphery of said platen and distribute the strokes of the type throughout the entire circumference thereof.

2. In a typewriting machine, a rotatable

- platen in combination with a detachable card-holder strip extending longitudinally on the face of said platen, and a plurality of devices spaced apart circumferentially 5 on said platen for attaching said strip at a plurality of different predetermined points on the periphery thereof, said strip being adapted for holding a card.
3. In a typewriting machine, in combination, a platen having heads at the ends thereof, a card holder strip adapted to lie against the face of said platen, a plurality of fastening devices carried by said heads separated circumferentially, and fastening 10 devices on said card-holder and adapted to 15 devices on said card-holder and adapted to

snap onto said first fastening devices to secure said card-holder on said platen.

4. In a typewriting machine, in combination, a platen having heads with a plurality of fastening devices arranged circumferentially thereupon, a card-holder strip extending along the face of said platen and projecting beyond the said heads, and snap-fasteners carried by said strip coöperating with said fastening devices.

JOHN C. McLAUGHLIN.
